INVENTOR
Alan L. Brown,
BY
Frederick Griswold
ATTORNEY

UNITED STATES PATENT OFFICE.

ALAN L. BROWN, OF PASSAIC, NEW JERSEY.

GAME.

Application filed August 10, 1921. Serial No. 491,184.

To all whom it may concern:

Be it known that I, ALAN L. BROWN, a citizen of the United States of America, residing at 95 Ascension Street, Passaic, county of Passaic, State of New Jersey, U. S. A., have invented a new and useful Improvement in and Relating to Games, of which the following is a specification.

This invention relates to that class of games or pastimes in which a player moves the position of a counter upon a chart or board according to the indications shown by an indicating means.

One object of the invention is to provide a game or pastime adapted for the use of grown people or children and consisting in a board or chart upon which certain definite routes or paths are shown leading in a roundabout way to a goal or home and adapted to be travelled by two or more players or contestants at the same time, the devious ways taken by the players being controlled by an indicating means.

Another object of the invention is to provide a novel indicating means for the invention in the form of a geometrical figure having a plurality of sides and so constructed and arranged that upon rolling or tumbling the body upon a smooth and or level surface, the body is adapted to come to rest with one of its faces uppermost. Said faces varying desired indications. Said uppermost face showing the next step or movement taken by the player.

A further object of the invention is to provide an indicating device as aforesaid, which is equally applicable to a variety of pastimes or games and in which the sides or faces present similar shapes and are so colored and bear such devices thereon as to enable the device to give a wide range of indications.

A still further object of the invention is the method whereby the indicating means is developed.

In order that this invention may be clearly understood and readily carried into effect, the same will now be described more fully with reference to the accompanying drawings illustrating a preferred embodiment thereof, and in which:

Fig. 1 is a plan of one form of board or chart upon which the game may be played.

Fig. 2 is an elevation of the indicating means.

Fig. 3 represents a preferred form of counter or piece used to represent a player.

Fig. 4 shows one face of the dodecahedron used in the development of the indicating means.

Fig. 5 shows a face of the icosahedron which may also be used in the development of the indicating means.

The game or pastime is adapted to be played by any number of players or contestants upon a chart or board, the preferred form of which is illustrated as a whole by 1, Fig. 1. Three starting points 2, 3, and 4, are shown each of which bear a different color to correspond with the colors appearing upon the faces of the indicating means, as will be hereinafter more fully described. A finishing point or home 8 is also shown at the opposite end of the board. In Fig. 1 the left hand starting point 2 is shown in dot and dash lines and these dot and dash lines are intended to represent the color green which in the present instance throughout the drawing will be used to represent lines. The central starting point 3 is shown in full lines and in this instance is intended to represent the color black. The right hand starting point 4 is shown in dashes to represent red and to correspond to the red faces of the indicating means.

In the present instance there has been disclosed a board 1 having three starting points, but it is obvious that more starting points could be incorporated on the board by increasing the size thereof should the faces of the indicating means, for instance, bear more than three different colors, as described more fully hereinafter.

Various paths or routes which the players may take are shown covering the whole of the playing surface of the chart. These paths are indicated in general at 5 and various portions of the lines are colored to agree with the colors appearing on the faces of the indicating means. I have indicated the colors of these lines similarly to the lines representing the corresponding colors at the starting point to wit, a dot and dash line for green, a full line for black and a line of dashes for red. These lines or paths are shown as intersecting at various points throughout the surface of the board and a circle has been described at each of these points of intersection as at 6. The distance between two successive points of inter-

section 6 along any one of the lines or paths is intended to represent one move or step during the playing of the game and each point 6 may therefore be considered as a 5 stop or station. The direction of travel along the various paths between two successive stops or stations is shown by the arrow 7.

Any form of counter may be used to indicate the relative position of the various contestants on their journey between one of the starting points 2, 3 or 4 and the finishing point or home 8. In the present instance I have illustrated a convenient form 10 of counter in Fig. 3.

It will be noted from an observation of Fig. 1 that the various paths 5 form a devious or roundabout but continuous route from the starting points 2, 3 and 4 to the 20 finishing point or home 8.

As will be more apparent hereinafter, the move made by each player during his turn of play will not be confined to the distance between successive stations 6 but the indicating means which it is preferred to use with this invention bears a number of designs or devices 10, each of which denotes the number of stations which may be passed over by one player during one move. A 25 counterpart of each of these designs is shown upon a separate card or upon the board 1 and in this instance they are illustrated as incorporated in the form of tables 11, upon the board 1 between the various 30 starting points. Opposite each device 10, is shown the number of stops or stations over which the player is entitled to move his counter during each play as described 35 more fully hereinafter.

40 The indicating means referred to as a whole by 9 Fig. 2, and which I prefer to use in connection with the board 1 just described, consists of a geometrical figure or solid which in the present instance is shown 45 as having 120 faces of equal area and similar shape, sixty of which form similar and equal scalene triangles while the other sixty are opposite and similar and equal scalene triangles. These triangular sides or faces 50 are so arranged that each of the most acute angles of the juxtaposed faces meet in groups of ten. The angles next in acuteness are arranged to meet in groups of six while the most obtuse angles are arranged 55 to meet in groups of four. These latter angles are each just less than a right angle.

60 The solid 9 may be known as an ekatonicosahedron or it may be called a hexakis—isosohedron or a dekakis—dodekahedron. It may be considered as being developed in either of the following ways, to wit, (a) as a development of the dodekahedron or (b) as a development of the icosahedron.

(a) From the dodekahedron. The regu-

lar dodekahedron is a solid geometrical figure bounded by twelve regular pentagons, three of which meet at each apex. Each regular pentagon may be divided into ten equal scalene triangles (e. g. triangles having three sides and three angles proportionately equal) by dropping perpendiculars from the center of the pentagon to each of the sides and connecting the said center and each apex or vertex. Now referring to Fig. IV of the drawings if the point A (the center of the pentagon) is raised in an axial direction with respect to the solid a distance approximating 1/60 of the diameter of the dodekahedron and the points C, E, G, K and M raised also in an axial direction with respect to the dodekahedron a distance approximately 1/160 of the diameter of the dodekahedron and these points connected, there will result 120 equal scalene triangles, each one on a different plane and forming the 120 faces of the ekatonicosahedron.

(b) From the icosahedron: The icosahedron is a solid bounded by twenty equilateral triangles, five of which meet at each apex. One of these triangles is shown in Fig. V. It is divided into six equal scalene triangles by dropping lines to each side and to each apex from the center. Now if the center A' be raised in an axial direction with respect of the icosahedron a distance of approximately 1/60 of its diameter and the points C', E' and G' raised in a similar manner a distance of approximately 1/160 of the diameter of the icosahedron and these points connected, there will be formed the solid of 120 equal sides or faces, the ekatonicosahedron.

I prefer to color sixty of these faces with one color (12) such as black, forty other faces with another color (13) such as red and the remaining twenty faces with still a different color (14) such as green. The various colors are of course alternated so that no two faces bearing the same color lie in juxtaposition. Each of the faces, I prefer to have bear a figure or design (10) and in the present instance thirty of the faces bear a triangle (15) as an indicating or identifying mark, twenty four other faces bear a circle (16), fifteen bear a semi-circle (17), twelve bear quadrants (18), ten bear trapazoids (19), eight bear chevrons (20), six bear spades (21), five bear diamonds (22), four bear clubs (23), three bear hearts (24), two bear crescents (25), and one bears a star (26). It will thus be seen that I have provided an identifying mark for each of the 120 faces or sides and as is evident from the figure the different marks are so arranged that no two marks of the same kind appear upon faces which lie in juxtaposition. It is obvious that

means of identifying the sides other than the above figures may be used, for instance, each side may be numbered.

In using this device or playing this game 5 any number of players may participate but for the sake of description, it will be assumed that three individuals are playing the game.

The first player who will be hereafter referred to as "A" rolls or tumbles the device upon the floor, table or other smooth and substantially level surface. Upon expending the energy given it by player "A" the body will come to rest with one of its 15 faces uppermost and parallel to the surface upon which it is rolled. It will be assumed that a green face is uppermost and that this face bears upon it a spade. From the table hereinbefore described, it will be 20 seen that the player is entitled to seven moves or in other words that he is entitled to move his counter from the starting point colored green and indicated at 2 in Fig. 1 over seven of the green paths between the 25 stops indicated in Fig. 1 in a continuous direction shown by the arrows to the stop or station marked 27. The next player, who will hereafter be referred to as "B", now takes the indicator and rolls or tumbles 30 it as described for "A". It will be assumed for the sake of the description that the face appearing uppermost is colored black and that this particular black face bears upon it the indication of a circle. From the table it 35 will be seen that "B" is entitled to a move of two. In other words "B" takes his counter and beginning at the black starting place moves in the direction of the arrows along the black line to the second station 40 marked 28. The third player hereafter known as "C" now rolls the indicator in the hereinbefore described manner and for the sake of simplifying the description it is assumed that a red face is uppermost and that this face bears a crescent. From the 45 table it is seen that "C" is entitled to a move over eleven stations to the stop marked 29. It is obvious, of course, that the three players might not have each turned up a 50 different colored face to begin with nor would they necessarily have to start from different starting points but the start in each instance might just as well have been made from one and the same starting point and depending entirely on the color appearing 55 on the uppermost face of the indicator.

The third player C having finished his move it is player "A's" turn. "A" again tumbles the solid and it is assumed that this 60 time a black face is uppermost and that the figure appearing on this face is a triangle, "A" is therefore entitled to one move along the black line from the stop indicated as 65 27 in the direction of the arrow to the station shown in Fig. 1 as 30. The players

continue in this manner until their counters reach the finishing point or Home. The first player finishing, of course, being the winner of the game. It is obvious that the 70 players may be called upon to pass each other along the route to the Home since more than one player may turn up the same color. Should the player, for instance, be at a station from which there is no leading line of the color turned up by his roll he will be 75 forced to stay at that stop until his next turn or until he rolls a color which enables him to leave the station. For instance he may be at station 31 and upon his next roll turn up a black face. As there is no black 80 path from 31 he cannot move but must wait until his next turn or until the time in which he turns up either a green or red face to pass beyond that station. The winner of the 85 game is, of course, the player whose counter first reaches the goal or home 8.

While I have described my invention in detail in its present preferred embodiment, it will be obvious to those skilled in the art after understanding my invention that 90 various changes and modifications may be made therein without departing from the spirit or scope thereof. I aim in the appended claims to cover all such modifications and changes.

What is claimed is:—

1. A game piece adapted to be tumbled which is formed as a solid provided with a plurality of similar triangular faces in excess of forty-eight, which faces bear distinguishing symbols arranged in groups, each face in each group having the same symbol and each group bearing a definite evaluated relation to every other group.

2. A geometrical solid, having a plurality 100 of equal triangular faces in excess of forty-eight and bearing on each of said faces a means of identification.

3. A geometrical solid having a plurality 110 of equal triangular sides in excess of forty-eight, colors appearing upon each of said sides, the colors on two juxtaposed sides being different.

4. A solid having 120 faces of equal area and similar shape.

5. A body having 120 faces of equal area and similar shape, 60 of said faces being similar and equal scalene triangles, and the other sixty of said faces being opposite and similar and equal scalene triangles.

6. A solid having 120 similar and equal triangular faces whereof the most acute angles of the juxtaposed faces meet in groups of ten, the angles of juxtaposed faces next in acuteness meet in groups of six and 125 the most obtuse angles of juxtaposed faces meet in groups of four.

7. A device of the character described having 120 equal faces, sixty of said faces being of one color, forty of said faces being 130

of another color, and twenty faces being of still another color.

8. In a device of the character described, a body having a plurality of sides bearing 5 means of identification, 30 of said non-adjacent sides having depicted thereon a triangle, 24 of said non-adjacent sides having depicted thereon a circle, 15 of said non-adjacent sides having depicted thereon a semi-circle, 12 of said non-adjacent sides having depicted thereon a quadrant 10 of said non-adjacent sides having depicted thereon a trapezoid, 8 of said non-adjacent sides having depicted thereon a chevron, 6 of said 10 non-adjacent sides having depicted thereon a spade, 5 of said non-adjacent sides having depicted thereon a diamond, 4 of said non-adjacent sides having depicted thereon a club, 3 of said non-adjacent sides having depicted thereon a heart, 2 of said non-adjacent sides having depicted thereon a crescent and one of said sides having depicted 15 thereon a star.

9. A body, the surface whereof is formed 20 of 120 similar triangular faces, each of said faces being disposed in a different plane, 60 of said non-adjacent faces being black in color, 40 of said non-adjacent faces being red in color, 20 of said non-adjacent faces

being green in color, each of said faces bearing 30 a further means of identification in the form of a figure, 30 of said non-adjacent faces having depicted thereon a triangle, 24 of said non-adjacent faces having depicted thereon a circle, 15 of said non-adjacent 35 faces having depicted thereon a semicircle, 12 of said non-adjacent faces having depicted thereon a quadrant 10 of said non-adjacent faces having depicted thereon a trapezoid, 8 of said non-adjacent faces having depicted thereon a chevron, 6 of said non-adjacent faces having depicted thereon a spade, 5 of said non-adjacent faces having depicted thereon a diamond, 4 of said non-adjacent faces having depicted thereon a club, 3 of said non-adjacent faces having depicted thereon a heart, 2 of said non-adjacent faces having depicted thereon a crescent and one of said faces having depicted 40 thereon a star.

In testimony whereof, I, ALAN L. BROWN, have signed my name to this specification in the presence of two subscribing witnesses, this fourth day of August, 1921.

ALAN L. BROWN.
